BOMB LOADING PRESS

Frank C. Wilson, Arcade, N. Y.

Application November 4, 1942, Serial No. 464,541

4 Claims. (Cl. 86—20)

This invention relates to improvements in hydraulic presses; and the features of the invention, although not necessarily so limited, may be availed of to particular advantage in connection with the loading of incendiary bombs.

The loading of an incendiary bomb, as ordinarily practiced, is carried out in stages, usually five, a predetermined amount of thermite being introduced into the bomb casing in each of the first four stages and the powder employed to ignite the thermite being introduced into the casing in the final stage. After each charge is introduced it is compressed, being subjected to a pressure of the order of twenty thousand pounds; and after the final compressing operation the firing mechanism is secured in place. In the charging and compressing operations described it is essential, in order to insure proper functioning of the bomb and of the firing mechanism, that the charges be subjected to substantially the same predetermined pressure in each stage and that upon completion of the final charging and compressing operation, the level of the final charge (the ignition charge) be at, or within close tolerance of, a predetermined distance from the open end of the casing.

One object of the present invention is to provide a press which will enable the charging of incendiary bombs in the manner described, and the performance of generally similar operations, accurately and expeditiously, this object contemplating a press which is so designed that any deviation with respect to the normal or standard in the volume of any charge after completion of the compressing operation will be indicated so as to enable a correction in subsequent charges to compensate for such deviation.

A further object is to provide an indicating device for the purpose described which may be employed in connection with presses of standard design, either as an original part of the press or as an attachment.

A still further object is to provide a novel design and arrangement of the parts of the press, whereby to obtain simplicity and economy in construction and accuracy and speed in operation.

The invention is illustrated in the accompanying drawings in which:

Figure 1 is a perspective view of a press embodying the features of the invention.

Figure 2 is an enlarged fragmentary view, partially in section and partially in elevation.

Figure 3 is a horizontal section taken along line 3—3 of Figure 2.

Figure 4 is a diagrammatic illustration of a bomb and the tamping elements employed in compressing the thermite and powder charges.

Figure 5 is a top view of the dual holder in which the bomb casings are clamped during the compressing operations.

Figure 6 is an enlarged fragmentary section through the holder.

The press, as illustrated, includes a hydraulic cylinder 10 which is mounted in a framework 11 above a table 12, the flow of actuating fluid to and from the cylinder 10 to actuate the ram 13 being through a conduit 14 and being controlled by a lever 15.

15. The casings 16 of the bombs to be loaded may be clamped in holders 17 and 18, which are supported on the table 12 between guide rails 19. The latter cooperate with the bases 20 of the holders so that either holder may be moved either 20 to a position beneath the ram 13 or far enough to one side thereof so that the companion holder may be moved to such position.

Each holder is adapted to support two casings in upright, side-by-side positions and, as illustrated, comprises mating sections 21 and 22, the former being fixed to the base and having a hinge connection 23 (Figure 5) at its rear edge with the latter. Opposing channels 24 in the holder sections accommodate the bomb casings. In 30 order to clamp the casings in the holder the section 22 carries a locking element 25. A rod 26 pivotally connects the latter to lugs 27 on the section, a handle 28 being provided to enable the locking element to be swung to a position 35 in which rollers 29 engage and move behind lateral extensions 30 (Figures 5 and 6) formed or provided on the section 21, each roller 29 being carried in a housing 31 which is pivotally mounted upon a pin 32 and which may be adjusted to, and locked in, various angular positions 40 on the pin by screws 33 and 34. Provision is thus made for causing the rollers 29 to engage the extensions 30 in a manner which will insure proper gripping of the casings and locking of the sections. To unlock the sections of the holder it is only necessary to swing the element 25 in a direction which will cause the rollers 29 to move from behind the projections 30. Thereupon the section 22 may be swung outwardly with respect to 45 the mating section, and the two casings removed. Tamping elements 35 which are adapted to be inserted in the bomb casings are employed in pairs 50 in connection with the press to compress the charges of thermite and powder introduced into 55 the casings in the loading operations. Preferably

each compressing operation is carried out with tamping elements of such a length that the limits of the range of movement of the ram will be the same, the tamping elements employed in the first stage being of the greatest length, those employed in the final stage being of the shortest and those employed in the intermediate stages being progressively shorter. In this connection it will be understood, of course, that after each compressing operation, the tamping elements employed in such operation are removed, the next charge is introduced into each casing and the succeeding compressing operation carried out with shorter tamping elements. The procedure described is illustrated in Figure 4 in connection with a single casing wherein the charges of a loaded casing are indicated at 36, the space remaining at the upper end of the casing being intended to accommodate a suitable firing mechanism.

The tamping elements are in the form of plungers and carry cross-pins 37 at their upper ends to facilitate their withdrawal from the casings after the compressing operations. At their lower ends those of the elements employed in connection with the thermite charges preferably are formed or provided with rib-like extensions 38 in order that the separate charges will interlock with one another in such a manner as to promote combustion.

In the operation of the press, casings to be loaded are arranged in one of the holders 17 or 18, as the case may be, and after they are locked in place the required charge is introduced into each, the proper tamping elements are inserted and the holder in them moved to a position under the ram. The latter is then actuated to compress the charges in the casings, a suitable gauge 39 indicating continuously the pressure to which said charges are subjected by the tamping elements. When the charges have been compressed to the desired degree the pressure may be released and the ram restored to its original position. The holder may then be moved to one side to enable removal of the tamping elements, the introduction of the new charges and the substitution of shorter tamping elements for the original elements.

The use of a pair of holders in the manner illustrated has the advantage that two operators may employ the same ram without interfering with one another, one operator employing the ram while the other is performing the preparatory operations which precede the use of the ram. In this connection it will be noted that the ram 13 is formed or provided with a head 40 which is enlarged with respect to the ram body, the size of the head being determined by the size of the bomb casings and the distance that they are spaced apart in the holders.

In accordance with the invention, means is provided whereby upon completion of the loading of each casing, the upper or exposed surface of the composite charge will be located at, or within a fixed tolerance of, a predetermined distance from the open end of the casing so as to insure proper functioning of the firing mechanism which is employed in connection with the bomb. For this purpose, an indicating device 41 is employed. The said device includes a tubular housing 42 (Figure 2) which is carried by a cross-bar 43 of the framework of the press. The bore of the housing is enlarged at its upper and lower ends to accommodate bearing sleeves 44 and 45. A rod 46 is mounted in said sleeves, the latter spacing the rod from the walls of the housing and permitting

its free axial movement parallel to the path traversed by the ram.

A sleeve 47 on the upper end of the rod 46 is adjustable lengthwise of the rod and may be secured in the desired position by a set screw 48. The latter is carried by an enlarged or head portion 49 of the sleeve while a reduced or body portion 50 thereof extends into the upper enlarged end of the bore of the housing, the diameter of the reduced or body portion being less than the enlarged portion of the bore so as to avoid frictional contact between the sleeve and the housing. Spaced annular marks 51 are scored or otherwise formed in, or provided on, the body portion of the sleeve. At its lower end the rod 46 carries an arm 52 which is adjustably secured in the desired position by the set screws 53. The said arm is forked at its outer end to lightly engage opposite sides of the ram body and is formed on its under side with a rounded projection 54 to provide point contact with the top of the head 40. It will thus be apparent that as the ram moves up and down between the limits of its range of movement, the rod 46 will move between corresponding limits, 25 the force of gravity causing the projection 54 on the arm 52 to maintain constant contact with the head of the ram.

The marks 51 cooperate with the top beveled edge 55 of the housing 42 to indicate the level of the charge in each casing in the holder when it has been subjected to the required pressure, that is upon completion of a working stroke of the ram. Assuming, for example, that the gauge 39 indicates that the charges in the casings have been subjected to such pressure, then if the top edge of the housing 42 is located between the two score marks, the level of the compressed charges lies within the permissible tolerance range and no compensation need be made in subsequent operations. If, however, the top edge of the housing 42 is located above the upper score mark 51 when the proper pressure is indicated upon the gauge, this signifies that the volume of the compressed charges is less than prescribed and additional material must be introduced in subsequent charges by way of compensation. When the top edge of the housing 42 is located below the lower score mark when the prescribed pressure has been reached, this indicates that the volume of the compressed charges is greater than called for and in subsequent operations this may be compensated by reducing the amount of material in the charges, it being noted in this connection that a portion of the upper end of the housing 42 is cut away as indicated at 56 in order that the exact location and the relative positions of both score marks can be observed at all times, although one or both of said marks may at certain times be located below the beveled edge 55.

It will thus be apparent that the press described has the advantage that the separate charges employed in loading a bomb may all be compressed to the same degree while at the same time the loading operations may be so conducted that the level of the composite charge may be accurately controlled. Although the press is described in connection with the loading of incendiary bombs, it is understood, of course, that this is by way of example only, the press being available for use in connection with various operations which call for the movement of the ram to a predetermined limit in its working stroke but wherein the actual limit is determined by the applied pressure. In such cases the position of the rod 46 also corresponds to the actual position of the ram

and, hence, the relation of such position with respect to a predetermined, correct, position will be indicated.

I claim as my invention:

1. An indicating device for a press adapted to be employed in connection with operations which call for movement of the ram to a predetermined limit in its working stroke but wherein a predetermined applied pressure determines the actual limit, said device including a tubular housing having a reference portion, an element which is movable lengthwise in said housing, an adjustable sleeve on said element, said sleeve bearing limit marks, and an arm carried by said element which is engageable with said ram, whereby as said element follows the movement of said ram, the relation of said marks with respect to said reference portion indicates the relation of the actual position of the ram with respect to the correct predetermined position.

2. An indicating device for a press adapted to be employed in connection with operations which call for movement of the ram to a predetermined limit in its working stroke but wherein a predetermined applied pressure determines the actual limit, said device including a tubular housing, the upper end of which is formed to provide a reference edge, an element which is movable lengthwise in said housing, an adjustable sleeve on the upper end of said element, said sleeve bearing spaced limit marks, and an arm carried by the lower end of said element, said arm seating on said ram and having a forked outer end which is engageable with opposite sides thereof, whereby as said element follows the movement of said ram

the relation of said marks with respect to said reference edge indicates the relation of the actual position of the ram with respect to the correct predetermined position.

3. The combination, in a press which includes a removable holder for a compressible charge and a pressure operated tamping element which subjects said charge to a predetermined pressure, of a gauge of the operating pressure of the tamping element and means for indicating whether, at the predetermined pressure, the volume of said charge is greater or less than that which has been predetermined to be correct, said means including an element which is movable with said tamping element to significant positions indicative of the relation of the actual volume of said compressed charge with respect to the correct predetermined volume.

4. The combination, in a press which includes a removable holder for a compressible charge and a pressure operated tamping element which subjects said charge to a predetermined pressure, of a gauge of the operating pressure of the tamping element and means for indicating whether, at the predetermined pressure, the volume of said charge is greater or less than that which has been predetermined to be correct, said means including a stationary tubular housing which acts as a guide and an element in said housing which is movable lengthwise therein with said tamping element to significant positions indicative of the relation of the volume of said compressed charge with respect to the correct predetermined volume.

FRANK C. WILSON.
